(57) **CLAIM**

The ornamental design for a portable worklight, as shown and described.

DESCRIPTION

FIG. 1 is a front top perspective view of a portable worklight showing my new design.

FIG. 2 is a front bottom perspective view thereof.

FIG. 3 is a front view thereof.

FIG. 4 is a rear view thereof.

FIG. 5 is a left view thereof.

FIG. 6 is a right view thereof,

FIG. 7 is a top view thereof.

FIG. 8 is a bottom view thereof; and,

FIG. 9 is a front top perspective view thereof showing the light module in an opened position.

The broken lines shown in the figures represent portions of the portable worklight that form no part of the claimed design.
